UNITED STATES PATENT OFFICE.

MAX DECKERT, OF CHICAGO, ILLINOIS, ASSIGNOR TO LINDSTRÖM, SMITH COMPANY, OF CHICAGO, ILLINOIS.

DESIGN FOR AN ELECTRIC LANTERN.

52,308.

Specification for Design.

Patented Aug. 27, 1918.

Application filed May 9, 1918. Serial No. 233,578. Term of patent 7 years.

To all whom it may concern:

Be it known that I, MAX DECKERT, a citizen of the United States, residing at Chicago, in the county of Cook and State of Illinois, have invented certain new, original, and ornamental Design for Electric Lanterns, of which the following is a specification.

The figure of the drawings is an elevation of an electric lantern, showing my new design.

What I claim is:

The ornamental design for an electric lantern, as shown.

In testimony whereof I affix my signature.
MAX DECKERT.
